UNITED STATES PATENT OFFICE.

FRANK HELLER AND KALLMAN HIRSCH, OF NEW YORK, N. Y.

CHILD'S CARRIAGE.

SPECIFICATION forming part of Letters Patent No. 487,050, dated November 29, 1892.

Application filed June 14, 1892. Serial No. 436,668. (No model.)

To all whom it may concern:

Be it known that we, FRANK HELLER and KALLMAN HIRSCH, both of New York city, New York, have invented an Improved Combined Child's Carriage and Cradle, of which the following is a specification.

This invention relates to a combined child's carriage and cradle of peculiar construction; and it consists in the various features of improvement more fully pointed out in the claims.

In the accompanying drawings, Figure 1 is a longitudinal section of our improved child's carriage and cradle with the box raised. Fig. 2 is a similar section with the box lowered; Fig. 3, a front view of Fig. 2 with post h broken away; Fig. 4, a top view of the running-gear with the wheels removed.

The letters a a' represent the front and rear axles of a carriage, connected to the side bars b , carrying the handle c , as usual. To the side bars b there are attached a pair of springs d , carrying the transverse rests or feet e . Upon the rests e there is set the removable box or body f of the carriage. It is held in place by means of a spring g , secured at its ends to the side bars b and carrying at its center a hook g' , that engages an eye f' , depending downwardly from the center of the bottom f^2 of box f .

To the center of the axles a a' there is secured a longitudinal bar h^2 , the ends of which are bent up to constitute a front upright post h and a rear upright post h' , which are thus intimately connected with each other and with the running-gear. Each post is provided at its upper end with a hook h^3 h^4 . The box f is provided at its front and rear with the eye f^3 and chain f^4 , which may be made

to engage with the hooks. When the box f is lowered upon the rests e and is attached by means of the hook g' and eye f' , the device constitutes a child's carriage; but if the hook g' is disengaged from the eye f' and the box is raised and suspended from the hooked uprights h h' the device constitutes a cradle, which will rock freely. It will be seen that when converted into a cradle the box f does not rock upon the running-gear, but is freely suspended over the same. Thus there is not a constant jar upon the wheels, the extent of lateral motion is increased, and but a slight expenditure of power is required.

What we claim is—

1. The combination of a child's carriage-gear having front and rear axles a a' , with springs d , rests e , supported thereby, a longitudinal bar h^2 , secured to the center of the axles and having upwardly-bent forward and rear ends to constitute posts h h' , and with a carriage-body adapted to be suspended from said posts, substantially as specified.

2. The combination of a child's carriage-gear having front and rear axles a a' and side bars b , with springs d , rests e , supported thereby, a longitudinal bar h^2 , secured to the center of the axles and having upwardly-bent forward and rear ends, a detachable body f , having an eye f' , and with a spring g , secured to the side bars and having hook g' for engaging the eye, substantially as specified.

FRANK HELLER.
K. HIRSCH.
